UNITED STATES PATENT OFFICE.

HANS VON WOLFORDS DORF, OF INDIANAPOLIS, INDIANA.

FEEDER FOR GRINDING-MACHINES.

1,246,193.

Specification of Letters Patent. Patented Nov. 13, 1917.

Application filed September 23, 1916. Serial No. 121,881.

To all whom it may concern:

Be it known that I, HANS VON WOLFORDS DORF, a citizen of the United States, and a resident of Indianapolis, county of Marion, 5 and State of Indiana, have invented a certain new and useful Feeder for Grinding-Machines; and I do hereby declare that the following is a full, clear, and exact description thereof, reference being had to the accompanying drawings, in which like letters 10 refer to like parts.

The object of this invention is to provide mechanical means for forcibly feeding material into a grinding machine. Heretofore 15 it has been customary to force the material into meat grinding machines by hand and this has always been accompanied with great danger of the hand becoming injured by coming in contact with the grinding mechanism. This invention is intended to overcome 20 said difficulty and make hand feeding unnecessary and yet accomplish the feeding by mechanical means which will not interfere with the operation of the grinding machine in any particular.

One feature of the invention consists in providing a feeding block which is adapted to enter the hopper or throat of the machine, and a lever or other mechanism for forcing 30 downward said feeding block and thereby forcing the material into the machine, which device may be removably secured to the hopper. Since the hopper or throat of the grinding machine is usually circular, the 35 feeding block is likewise circular, and since the grinding mechanism in the machine is circular, the inner end of the feeding block is made concave transversely of the machine, but straight longitudinally of the machine.

40 The full nature of the invention will be understood from the accompanying drawings and the following description and claim.

Figure 1 is a central vertical cross section through the hopper and detachable means 45 with the feeder in elevation. Fig. 2 is a perspective view of the detachable means shown in Fig. 1.

There is shown herein a grinding machine of well known type having a cylinder 10 50 with a hopper or throat 11 at one end thereof through which the material is fed through the machine.

The material is fed into the machine forcibly by a feeding block 15 which is cylindrical to conform to the cylindrical form of the throat or hopper and the inner end is concave transversely of the machine, but is straight longitudinally of the machine. An arm 116 extends centrally from the feeding block 15 and by means of a pin 16 is pivoted in one of the holes 17 of a hand lever 18. Said hand lever is fulcrumed at one end by a pin 19 to ears 26 secured to the detachable means. The hand lever, therefore, when in its lower position, extends across the hopper, when the block is lowered, which enables one to feed the material to the grinder with considerable force. When the feeding block is withdrawn and the hand lever forced upward and back, the latter will be limited in its movement by a spring 21 which is a flat spring extending up behind the lever.

This enables the material to be forced in with considerable power and the feeding 75 block will not touch the grinder because of the concave form of the inner end of the block. Since the block is pivoted to the handle, as the handle is lowered, the block will automatically enter the throat of the machine without ever catching therein. By having a number of holes 17 in the handle, the block can be pivoted at the right point in the handle to cause the proper entrance and withdrawal thereof from the throat of 80 the machine. Since the lower end of the block is concave transversely of the grinder, it will force the material down so that the thickness of the layer of material above the grinder will be substantially uniform at all 85 points which is an important feature of the invention.

The detachable means which is the main 95 feature of this invention for attaching the feeding device to grinding machines previously made, consists of a frame 25 on which the upwardly extending ears 26 to which the handle is fulcrumed are secured and an inwardly curved extension 27 that rests upon the inner surface of the hopper and an outward downwardly extended portion 28 which projects outside of the hopper and below the top thereof and carries a set screw 29 whereby it is secured to the hopper.

The invention claimed is:

The combination with a grinding machine having a hopper through which material is supplied to the machine, of a feeding block adapted to enter the hopper and force the material into the machine, a lever to which said feeding block is pivoted, a frame adapt-

ed to fit astride one side of the hopper for fulcruming said lever, and means for detachably securing said frame to the hopper. 10

In witness whereof, I have hereunto affixed my signature.

HANS VON WOLFORDS DORF.
